UNITED STATES PATENT OFFICE.

ALEXANDER C. RINDSKOPF, OF CHICAGO, ILLINOIS, ASSIGNOR TO PFANSTIEHL RADIO COMPANY, A CORPORATION OF ILLINOIS.

DESIGN FOR A LOUD SPEAKER.

Application filed July 6, 1926. Serial No. 18,256. Term of patent 7 years.

To all whom it may concern:

Be it known that I, ALEXANDER C. RINDSKOPF, a citizen of the United States, residing at Chicago, county of Cook, and State of Illinois, have invented a new, original, and ornamental Design for a Loud Speaker, of which the following is a specification, reference being had to the accompanying

drawing, forming a part hereof, in which the drawing is a view in perspective of the loud speaker.

I claim:

The ornamental design for a loud speaker as shown.

ALEXANDER C. RINDSKOPF.
